Filed Aug. 11, 1972, Ser. No. 279,822

Term of patent 14 years

Int. Cl. D22—05

U.S. Cl. D22—29

FIG. 1

FIG. 4

FIG. 2

FIG. 3

FIG. 1 is a bottom plan view of a fishing lure showing my new design, with respect to which view it is noted that the characteristic shape of the central portion shown is curved outwardly toward the position of the viewer;

FIG. 2 is a side elevational view of the fishing lure depicted in FIG. 1;

FIG. 3 is a top plan view of the fishing lure depicted in FIGS. 1 and 2, such view showing that the central portion of the lure is curved inwardly away from the eye of the viewer; and

FIG. 4 is a bottom plan view of another embodiment of my new design, the only difference in this embodiment

and the embodiment illustrated in FIGS. 1-3 being that the embodiment of FIG. 4 has no eyes.

I claim:

The ornamental design for a fishing lure, as shown and described.
